Specification for Design.

Patented July 13, 1920.

Application filed March 5, 1919. Serial No. 280,867. Term of patent 14 years.

To all whom it may concern:

Be it known that I, CHARLES RALPH TOWNSEND, a subject of the King of Great Britain, residing at Caxton House, Great Charles street, Birmingham, in the county of Warwick, England, have invented a new, original, and ornamental Design for a Clamping-Dog, of which the following is a specification, reference being had to the accompanying drawings, forming part thereof.

Figure 1 is a side elevation of a clamping dog showing my new design,

Fig. 2 is a top plan,

Fig. 3 is a bottom plan,

Fig. 4 is a transverse section on the broken line Fig. 1.

I claim:

The ornamental design for a clamping dog as shown.

CHARLES RALPH TOWNSEND.
